Littenberg, Krumholz & Mentlik, LLP

(57) **CLAIM**

The ornamental design for a power base for desk mount arm,
as shown and described.

DESCRIPTION

FIG. 1 is a front perspective view of a power base for desk mount arm of my design, according to a first embodiment; FIG. 2 is a front elevational view thereof;

FIG. 3 is a top plan view thereof;

FIG. 4 is a front perspective view of a power base for desk mount arm of my design, according to a second embodiment;

FIG. 5 is a front elevational view thereof;

FIG. 6 is a top plan view thereof;

FIG. 7 is a front perspective view of a power base for desk mount arm of my design, according to a third embodiment;

FIG. 8 is a front elevational view thereof;

FIG. 9 is a top plan view thereof;

FIG. 10 is a front perspective view of a power base for desk mount arm of my design, according to a fourth embodiment;

FIG. 11 is a front elevational view thereof;

FIG. 12 is a top plan view thereof;

FIG. 13 is a front perspective view of a power base for desk mount arm of my design, according to a fifth embodiment;

FIG. 14 is a front elevational view thereof;

FIG. 15 is a top plan view thereof;

FIG. 16 is a front perspective view of a power base for desk mount arm of my design, according to a sixth embodiment;

FIG. 17 is a front elevational view thereof;

FIG. 18 is a top plan view thereof;

FIG. 19 is a front perspective view of a power base for desk mount arm of my design, according to a seventh embodiment;

FIG. 20 is a front elevational view thereof;

FIG. 21 is a top plan view thereof;

FIG. 22 is a front perspective view of a power base for desk mount arm of my design, according to an eighth embodiment;

FIG. 23 is a front elevational view thereof;

FIG. 24 is a top plan view thereof;

FIG. 25 is a rear elevational view of a power base for desk mount arm, according to all embodiments;

FIG. 26 is a right side elevational, the left side view being a mirror image thereof, according to all embodiments; and,

FIG. 27 is a bottom plan view, according to all embodiments.

(Continued)

The broken lines shown in the drawings are for the purpose of illustrating environmental structure and form no part of the claimed design. The dot-dash lines are boundary lines and form no part of the claimed design.

1 Claim, 27 Drawing Sheets
